BREAD BOX

Mel Appel, Livingston, and Martin Schnur, West Orange,
N.J., assignors to Elpo Industries Inc., Fair Lawn, N.J., a corporation of New Jersey

Filed Feb. 8, 1967, Ser. No. 5,720

Term of patent 14 years

(Cl. D44—6)

FIG. 1

We claim:

The ornamental design for a bread box, as shown and described.
